UNITED STATES PATENT OFFICE.

GEORGE W. ROWE, OF GLENWOOD, NEW MEXICO.

GATE-OPENER.

1,286,117.

Specification of Letters Patent. Patented Nov. 26, 1918.

Application filed April 30, 1918. Serial No. 231,636.

To all whom it may concern:

Be it known that I, GEORGE W. ROWE, a citizen of the United States, residing at Glenwood, in the county of Socorro, State 5 of New Mexico, have invented certain new and useful Improvements in Gate-Openers; and I do hereby declare the following to be a full, clear, and exact description of the invention, such as will enable others skilled in 10 the art to which it appertains to make and use the same.

This invention relates to new and useful improvements in farm gates and particularly to openers therefor.

One object of the present invention is to provide a novel and improved mechanism whereby the gate can be easily and quickly opened from either side and closed from either side after having passed through the 20 gateway.

Another object is to provide a novel and efficient means for throwing the hinged side of the gate off center to cause the gate to swing into opened or closed position.

Other objects and advantages will be apparent from the following description when taken in connection with the accompanying drawing.

In the drawing:

30 Figure 1 is an elevation of a gate made in accordance with my invention.

Fig. 2 is a top plan view of the device in the position of Fig. 1.

Fig. 3 is a top plan view of the device 35 showing the gate in open position.

Fig. 4 is a fragmentary elevation of the device, partly in section.

Referring particularly to the accompanying drawings, 10 represents the post of the 40 gate 11, and 12 the sill thereof. The bottom of the post 10 is stepped into a socket 13 in the inner end of the sill 12, while the upper end extends a suitable distance above the upper end of the gate where it is provided 45 with an anti-friction roller 16. Carried by the upper end of the post 14, which is fixed in the sill 12, is a horizontally disposed rectangular frame 15, the same extending at right angles from the post and receiving 50 the roller carrying end of the post 10 therein. The post 14 carries a vertically extending eye member 17 on the top thereof, and slideable through this eye member is a hollow member 18 which has one end formed with

an eye 22. Slidable in the other end of the 55 member 18 is a rod 19 which is formed with an eye 19' receiving the upper end of the post 10 therethrough.

Disposed at opposite sides of the gate are the posts, each having a grooved roller 21 60 on its upper end. Secured to the eye 22 of the member 18 are the two wires 20 each of which extends to and passes over one of the grooved rollers and depends at the side of the post where it is provided with a 65 handle 23.

Thus when either of the wires is pulled, the member 18 will rotate with the eye 17 at its pivot with the result that the post 10, which inclines toward the post 24 of the gate- 70 way, will be swung to one side of the frame 15 and rest in one of the side angles thereof, thus canting the gate so that it will swing into and remain in open position, until the other wire is pulled, when the post 10 will 75 be moved into the forward angle of the frame. When the wire is pulled, the gate will be canted into such an angle that the pivoted latch bar 27 which is carried by the free end of the gate, will be raised out of 80 engagement with the notch 26 of the keeper 25 of the post 24. When the gate swings into closed position, this bar will move on its pivot and rise up the incline of the keeper and drop into the notch thereof, thus 85 holding the gate in closed position.

What is claimed is:

A gate operating mechanism including a stationary post, a post forming a part of the gate and pivotally mounted in an inclined position adjacent the first post, a horizontally extending angular frame carried by the first post and receiving the upper portion of the inclined post, an L-shaped lever pivotally mounted on the stationary 90 post, said lever having an elongated slot in the horizontal arm thereof receiving the upper end of the inclined post therein for movement thereof into the interior angles of the said frame, and means for rocking the 95 lever.

In testimony whereof, I affix my signature, in the presence of two witnesses.

GEORGE W. ROWE.

Witnesses:

JOE CAMPBELL,
JOE LORIE.
